United States Patent [19]

Johnston

[11] Patent Number: Des. 412,887

[45] Date of Patent: ** Aug. 17, 1999

[54] SCALABLE PROCESSING ARCHITECTURE (SPARC) COMPUTER MOTHERBOARD

[75] Inventor: **Mark L. Johnston**, Los Altos, Calif.

[73] Assignee: **Cycle Computer Corporation**, Cupertino, Calif.

[**] Term: **14 Years**

[21] Appl. No.: **29/061,332**

[22] Filed: **Oct. 22, 1996**

Related U.S. Application Data

[63] Continuation of application No. 29/038,145, Apr. 27, 1995, Pat. No. Des. 374,866.

[57] CLAIM

The ornamental design for a scalable processing architecture (SPARC) computer motherboard, as shown and described.

DESCRIPTION

FIG. 1 is a perspective view of a first embodiment of the scalable processing architecture (sparc) computer motherboard embodying my new design;

FIG. 2 is a top elevational view thereof;

FIG. 3 is a back side view thereof;

FIG. 4 is a front side view thereof;

FIG. 5 is a right side view thereof;

FIG. 6 is a left side view thereof; and,

FIG. 7 is a bottom view thereof.

The broken line showing throughout the drawing views is included for the purpose of illustrating environmental structure.
